UNITED STATES PATENT OFFICE

CARL E. SPINNEY, OF WEST LAFAYETTE, INDIANA

AUTOMATIC TANK LOADER FOR FUEL TRUCKS

Application filed October 1, 1927. Serial No. 223,313.

My invention relates to improvements in automatic tank loaders for fuel trucks. The invention will be explained as embodied in apparatus employed for filling the fuel trucks from the storage tanks of a refinery or refinery sub-station.

An object of the invention is to provide an improved automatic tank loader for fuel trucks.

10 Another object is to provide an automatic tank loader which reduces the time for filling the tanks of a fuel truck as compared with the present gravity or pressure feed apparatus.

15 Another object is to provide in an automatic tank loader means for automatically shutting off the flow of fuel to the tank when the fuel level reaches its maximum height.

20 A further object is to provide in an automatic tank loader selective apparatus for quickly connecting various supply tanks with a common discharge tube, thus making it possible to successively feed several different fuels or liquids through the discharge tube as required in a relatively short time.

25 A further object is to provide in an automatic tank loader means for draining the contents of the common discharge tube when not in use into one of several auxiliary tanks so as to leave the discharge tube in readiness for the conduction of other fuels or liquids therethrough.

30 A further object is to provide an automatic tank loader by use of which the fuel is conducted to the tank through its normal discharge pipe, thus leaving that pipe filled with fuel when the filling operation is finished.

35 Other objects and advantages will be more particularly pointed out in the following specification and appended claims.

An embodiment of the invention is illustrated in the accompanying drawings forming a part of this application, in which:

40 Figure 1 is a vertical sectional view through main supply tanks and the tank of a fuel truck;

45 Figure 2 is an enlarged sectional view of a part of the apparatus illustrated in Figure 1;

50 Figure 3 is an enlarged sectional view of a part of the apparatus illustrated in Figure 1;

Figure 4 is a sectional view along the line 4—4 of Figure 6;

Figure 5 is a sectional view along the line 5—5 of Figure 6;

Figure 6 is an enlarged sectional view, 55 parts thereof broken away, of the fuel tank and discharge tube connections;

Figure 7 is an enlarged sectional view of the part of the apparatus illustrated by Figure 1;

Figure 8 is a view similar to Figure 6 but with the valve parts open as in filling the fuel tank; and

Figure 9 is a sectional view along the line 9—9 of Figure 6.

In general the invention consists of refinery or sub-station supply tanks A and B, one above the other, containing fuel under air pressure, a selector valve mechanism C for connecting a common discharge tube D with one of four sets of tanks A and B, a fuel truck tank E having a discharge pipe F and connecting mechanism G of special construction for connecting the discharge tube D with the discharge pipe F of the fuel tank. This 70 mechanism G embodies a valve generally indicated at H which is manually opened and which closes automatically upon the actuation of a float J in the fuel tank at maximum fuel level height. 75

In the ordinary refinery or sub-station several sets of tanks A and B are housed in structures 10 over which railway tank cars travel upon rails 11 and discharge their contents into the tanks below. Considering but one set of the tanks A and B as shown in Figure 1, the upper or tank A is connected by passage 12 with tank B, there being a shut-off valve 13 for isolating the tanks from one another. Compressed air is admitted to the tanks A and 80 B through passages 14 and 15 respectively so that fuel is forced into tank B by application of compressed air at 14 when the valve 13 is open and the discharge of fuel from tank B through its discharge pipe 16 is hastened upon 85 the application of air under pressure at 15 with valve 13 closed.

The selector valve mechanism C for connecting the flexible discharge tube D with one of several sets, in the present illustration there 90

are but four contemplated, consists in a valve casing 20 connected by passages 21 with discharge pipe 16 of tank A and pipes 22, 23 and 24 from other tanks not shown which may contain, for the purpose of illustration, high test gasoline, furnace oil and kerosene respectively, whereas tank B illustrated in Figure 1 may contain ordinary gasoline.

A rotatable sleeve shut-off valve 25 is disposed within casing C and has four openings 26 therethrough, each of which register with one of the passages 21 simultaneously, when sleeve 25 is rotated as by manipulation of an arm 30 extending radially from the outer end 15 of the valve sleeve.

A selector valve sleeve 32 is closely fitted and rotatable within valve sleeve 25 and has four openings 33 therethrough, one of which is not shown in Figure 2, disposed at intervals 20 along the length of the valve sleeve so as to register selectively with the passages 21 as valve sleeve 32 is rotated by means of manual manipulation of an arm 34, extending radially from the sleeve at a point adjacent to lever 30. Valve sleeve 32 is connected by a union to flexible discharge tube D.

The opposite end of discharge tube D is connected by a coupling member 40 to a fuel tank nozzle connecting member of special 30 construction which consists of a cylindrical body 41 adapted to fit within the discharge nozzle 42 of the fuel tank E and to be held there in place by a connecting ring 43 by bayonet connecting members 44. Rotation of ring 43 in opposite directions serves to fasten and release the parts respectively.

Cylinder 41 is further provided at its outermost end with a circular valve seat 48 for receiving a valve 49 carried upon a stem 50 40 mounted for reciprocable movement longitudinally of cylinder 41 and yieldingly held upon its seat 48 by a compression spring 51 one end of which bears upon a transverse pin 52 carried at the outer end of stem 50 and at 45 the other end upon the adjacent face of one of the stem supports 53. That portion of the stem 50 extending beyond support 53 is sufficiently long to permit the valve to move to the position shown in Fig. 8.

50 The fuel tank discharge nozzle is carried by a chamber 60 which is in turn connected at 61 with discharge pipe F of the fuel tank.

Chamber 60 has a valve 62 disposed therein which is carried by a longitudinal reciprocable rack 63, the teeth 64 of the rack being in mesh with a pinion 65 so that rotation of the pinion will cause longitudinal movement of the rack to move valve 62 toward and away from its seat 65'. Seat 65' is formed at the innermost end of discharge nozzle 42. A compression spring 66 disposed concentric with the rack 63 serves to urge valve 62 toward seat 65'.

65 With reference to Figure 9, pinion 65 is fixed upon a shaft 70 which is rotatably

mounted in an upper portion of chamber 60 and which has an externally extending part 71, angular in cross-section, for engagement with a socket wrench or crank 72 by means of which pinion 65 may be rotated by 70 rotating shaft 70.

Valves 49 and 62 are automatically interconnected upon the projection of cylinder 41 within nozzle 42 and turn in a clockwise direction. This is because valve 49 has a 75 pair of diametrically opposed loops 73 on its outer face and valve 62 has a pair of registering hook members 74 for engaging with loops 73 of valve 49. Thus, upon movement of valve 62 valve 49 will follow at all times 80 when the discharge tube D is connected with discharge pipe F as described.

Upon filling tank E the operator will elevate valve 62 by rotation of shaft 70 with crank 72 engaged at 71 with shaft 70 until 85 the apparatus assumes the position shown in Figure 8. Shaft 70 has a notch 80 on its outer surface which engages with the tooth 81 of a pivotally mounted dog 82 so that the dog normally prevents rotation of shaft 70 90 in a counter-clockwise direction, i. e., that direction which the shaft rotates upon the closing of valve 62—49.

The outermost end of dog 81 engages with a plunger rod 84 carried by a piston 85 by 95 gravity which is disposed within a cylinder 86 containing a non-compressible medium such as oil. A compression spring 87 urges piston 85 inwardly of the cylinder but yields upon the application of pressure within the 100 cylinder so as to permit the piston to move toward dog 82 and thus release the dog from the shaft so that the springs 51 and 66 may jointly act in closing valves 49 and 62.

Cylinder 86 is connected by a small tube 105 87 with a cylinder 88 having a piston 89 therethrough carried by a float 90 the cylinder 88 is the inverted end of the tube 87. Float 90 (see Figure 1) is disposed within the dome 92 of fuel tank E and at the maximum fuel level height so that when fuel in tank E has reached that height, float 90 will be lifted, thus causing piston 89 to move and increase the oil pressure in cylinder 88 and consequently cylinder 86 sufficient to move 115 piston 85 and disengage dog 82 from shaft 70. This permits springs 51 and 66 to act in the manner described in closing valves 49 and 62.

In order that all of the liquid in discharge 120 tube D may be removed from the tube prior to its use for conducting other fluids or liquids, tube D is connected at 95 with a valve chamber 96 having a slide valve 97 therein for selectively connecting the valve chamber 96 with one of four passages 98 which lead to auxiliary tanks corresponding to the tanks connected with pipes 16, 22, 23 and 24 respectively. Slide valve 97 is operated by movement of a handle 99 con- 130

5 nected with the valve stem 100 which registers with a marked indicator slot 101.

In operation the truck bearing fuel tank E is moved to the position shown in Fig. 1 and cylinder 41 forming a part of the discharge nozzle of pipe D is inserted within nozzle 42. Cylinder 41 is turned slightly to the right to cause hooks 74 to engage with loop 73, thus interlocking valves 49 and 62.

10 Assuming that the operator wishes to deliver gasoline from tanks A and B into fuel tank E, the selector valve sleeve 32 is rotated by means of arm 34 until the opening 33 therein registers with pipe 21 associated 15 with pipe 16. He then moves arm 30 so as to cause valve sleeve 25 to move, thus registering openings 26 with pipes 21. Shut-off valve 13 is closed and compressed air applied at 15. Shaft 70 is then rotated by crank 72 20 (see Fig. 9) to elevate valve 62 and valve 49 to the position shown in Fig. 8 in the manner described.

Gasoline from tank B will thereupon be forced through delivery tube D and discharge 25 pipe F of tank E into tank E. When the pipe level of fuel therein reaches float J the float will move with the rising level, causing piston 89 to move in cylinder 88 and the oil in cylinder 88, pipe 87 and cylinder 86 will be 30 placed under pressure sufficiently to move piston 85, thus releasing dog 82. Upon the releasing of dog 82, springs 66 and 51 both function to close valves 49 and 62 simultaneously, thus shutting off the flow of gasoline into fuel tank E.

The air pressure in tank B is then shut off, valve sleeve 25 is turned by arm 30 to shut off tube D from pipes 21 and the fuel then in tube D is drained into one of the four 40 auxiliary tanks connected with pipes 98 which is reserved for gasoline by manipulation of valve 97. During the tank filling process valve 97 is elevated so that the lower portion of the valve closes the lower end of pipe 95 which communicates with valve 45 chamber 96.

Fuel from tank A is now forced into tank B to replace the fuel exhausted therefrom by the opening of valve 13 and the application of compressed air at 15. Thus tank B is ready for subsequent fuel tank filling operations in the manner described.

It is apparent from the foregoing description of the tank filling mechanism that the time for filling tank E may be greatly reduced over the present process for tank filling which requires watching the rising level of fuel therein and the slowing up of the fuel supply as it approaches the top of the tank. 50 With the present mechanism fuel may be forced into fuel tank E at maximum speed throughout the entire filling operation since valves 49 and 62 close instantly upon the arrival of the fuel level at its maximum height.

65 I claim:

1. In combination, a fuel receiving tank having a discharge nozzle, a fuel discharge tube arranged for connection with the discharge nozzle of the receiving tank, a valve in said discharge nozzle, a valve associated with said discharge tube at that end connected with the discharge nozzle, means for interconnecting said valves, a spring associated with each valve for urging the valves into closed position, manually operable means for opening the valves, a dog for holding the valves in open position, and float operated means in the receiving tank for releasing the dog to permit the valves to close when the level of fuel therein reaches a predetermined height. 70

2. The combination with a tank having a discharge nozzle and a discharge tube, means for connecting the nozzle to the tube, a valve in the discharge nozzle for shutting off the flow of fuel therethrough, means for opening and for closing said valve, and a valve disposed in the adjacent end of the discharge tube arranged to inter-connect with the valve in the discharge nozzle when the tube is connected with the nozzle whereby operation of the first named valve causes the last named valve to move therewith and means for operating said valves in response to the liquid level in said tank. 80

3. In combination, a fuel receiving tank, a discharge tank, a discharge nozzle for the tank through which fuel may be admitted to and discharged from the tank, a fuel discharge tube for connection with said nozzle, a valve in the discharge nozzle, a valve in the fuel discharge tube, and means for actuating both of said valves when the fuel in the tank reaches a predetermined level. 90

4. In combination, a fuel receiving tank, a discharge nozzle for the tank through which fuel may be admitted to and discharged from the tank, a fuel discharge tube for connection with said nozzle, a valve in said nozzle, a valve in said tube, said valve being in juxtaposition whereby no fuel is intervening the valves and means for closing both of said valves when the fuel in the tank reaches a predetermined level. 100

5. In combination, a fuel receiving tank, a discharge nozzle for the tank through which fuel may be admitted to and discharged from the tank, a fuel discharge tube for connection with said nozzle, a valve in the discharge nozzle and a spring for normally holding said valve closed, a valve for the discharge tube and a spring for normally holding said valve closed, means for opening said valves in unison and means responsive to the fuel level in said tank for causing said spring to close said valves in unison. 110

6. In combination with a fuel receiving tank, a discharge nozzle for the tank through which fuel may be admitted to and discharged from the tank, a fuel discharge tube for con- 120 130

nection with said nozzle, a valve in the discharge nozzle, a valve in the discharge tube, means for normally closing said valves and latch mechanism for holding said valves in their open position, a cylinder for actuating said latch mechanism in response to fluid pressure, a fluid pressure producing cylinder mounted in said tank, and means responsive to the fuel level in said tank for producing a fluid pressure in said last mentioned cylinder thereby releasing the latch mechanism to close said valves.

7. In combination with a discharge nozzle and a discharge tube, a valve in the discharge nozzle for shutting off the flow of fuel therethrough, a valve disposed in the adjacent end of the discharge tube, means for coupling the discharge nozzle and tube while the valves remain closed, means for opening and closing said valves while the nozzle and tube are coupled.

8. In combination with a discharge nozzle and a discharge tube, a valve seat in the discharge nozzle, a valve seat in the discharge tube, means for coupling said nozzle and tube whereby the valve seats are brought adjacent each other, a valve in said discharge nozzle, a valve in said discharge tube, and means for interconnecting said valves whereby the opening and closing of one of said valves will result in opening and closing of the other respectively.

In witness whereof, I hereunto subscribe my name this 26 day of September, 1927.

CARL E. SPINNEY.
